UNITED STATES PATENT OFFICE.

STEPHEN M. HAMBLIN, OF CENTRAL FALLS, RHODE ISLAND, ASSIGNOR TO THE NEW SHUTTLE COMPANY, OF PAWTUCKET, RHODE ISLAND.

SELF-THREADING LOOM-SHUTTLE.

SPECIFICATION forming part of Letters Patent No. 630,051, dated August 1, 1899.

Application filed March 24, 1899. Serial No. 710,285. (No model.)

To all whom it may concern:

Be it known that I, STEPHEN M. HAMBLIN, a citizen of the United States, residing at Central Falls, in the county of Providence and State of Rhode Island, have invented certain new and useful Improvements in Self-Threading Loom-Shuttles, of which the following is a specification, reference being had therein to the accompanying drawings.

10 In the said drawings, Figure 1 is a plan of portion of a loom-shuttle embodying my invention. Fig. 2 is a side elevation thereof. Fig. 3 is a plan of the educt-tube, the latter being shown separately. Fig. 4 is an end elevation thereof. Fig. 5 is an inverted or bottom view thereof. Fig. 6 is a view thereof, looking from the left-hand side in the other figures.

15 1 designates the body of a loom-shuttle; 2, the spindle thereof; 3, a cop on the said spindle; 4, a yarn-passage in the forward portion of the shuttle-body in line with the said spindle, and 5 the threading-chamber, which is formed in the shuttle-body at the forward end 25 of the said yarn-passage 4.

20 6 designates a depression which I form in the upper side of the forward portion of the shuttle-body in advance of the threading-chamber 5, the said depression constituting a continuation or extension of the said threading-chamber and having an inclined bottom which slopes upwardly and forwardly from the threading-chamber, as is indicated clearly in dotted lines in Fig. 2.

25 35 7 designates the educt-tube. It is inserted in the delivery-eye of the shuttle, as shown in Figs. 1 and 2, and its length extends transversely across the shuttle. Its inner end is in line with the axis of the shuttle-body and spindle, so that the yarn paying off from the cop upon the spindle leads around the said inner end in traveling on its way through the educt-tube, the said inner end of the educt-tube serving as a means of guiding the yarn from the spindle and enabling it to change its direction of movement. A threading-slit 8 extends from one end of the educt-tube to the other. From the upper side of that portion of the educt-tube which projects inwardly 40 into the threading-chamber 5—that is to say, from the upper edge of the threading-slit 8—a

threading-tongue 9 extends forwardly into the depression 6. The extremity of the said threading-tongue 9 lies near the sloping bottom of the said chamber 5, with usually a slight upward bend at its tip to facilitate the operation of introducing the yarn under the said tip in threading the shuttle. The forward extremity of the said threading-tongue 9 crosses the continuation of the axis of the spindle. In the operation of threading as the yarn is drawn by hand forward off the spindle lengthwise of the shuttle it is at the same time moved so that it shall be carried downward into the passage 4, chamber 5, and depression 6. The yarn in consequence of being simultaneously advanced and depressed will travel along the inner side edge of the said tongue and be deflected thereby until it drops off the end of the tongue, whereupon it will 70 pass under the laterally-projecting tip of the tongue, thus assisting in getting the yarn under the tongue. The outer edge of the tongue 9 inclines outwardly from its tip to its base, being formed with an easy compound curve 75 in the illustrated embodiment of the invention. The said edge is located so that it terminates at the beginning of a slit formed in the shuttle-body and communicating with the delivery-eye, the said slit having the vertical 80 portion 10 extending diagonally across the outer part of the shuttle-body from the chamber 5 to the outer face of the shuttle-body and downward to the level of the delivery-eye and the horizontal portion 11 intersecting both the 85 said vertical portion and also the delivery-eye. The slit 8 is carried around to the upper side of the educt-tube 7, in the outer portion of the latter, so that the outer end of the said slit 8 is convenient of access from the 90 said horizontal portion 11 of the slit in the shuttle-body.

95 In threading the shuttle after the yarn has been drawn forward and caught under the tip of the threading-tongue 9 in the manner which has been described already the portion of the yarn which is held in the hand of the weaver is carried rearwardly along the outer edge of the tongue 9 and also along the rearwardly-extending diagonal slit 10 in the shuttle-body. It next is depressed to carry it 100 down in the slit 10 into the horizontal slit 11.

Finally it is carried forward to draw it along the slit 11 to the slit 8 in the educt-tube 7, it being depressed to carry it through slit 8 into the interior of the said educt-tube.

5 12 12 designate inwardly-extending lips or spurs which are provided at opposite sides of the outer end of slit 8 in educt-tube 7. These lips or spurs are separated from each other widely enough to permit the yarn to 10 pass freely between the same in the operation of threading; but it is practically impossible for the yarn to find its way out between them again unless purposely aided by the hand of the weaver. In some cases a single lip or 15 spur may be used. For the purpose of securing the educt-tube in place, it is provided with a projecting ear or lug 13, suitably formed upon or secured to the same and having a hole 131 therethrough, through which 20 hole is passed a securing-screw 14, by means of which the said ear or lug is clamped against a shoulder or ledge 15 at the bottom of the chamber 5.

I claim as my invention—

25 1. The combination with a shuttle-body having a delivery-eye extending through one side thereof and a threading-slit communicating with the said eye, of the educt-tube extending transversely of the shuttle with its 30 outer portion cylindrical and located in the said delivery-eye, the said tube having the threading-slit which is reached through the said slit in the shuttle-body and also having the threading-tongue projecting forwardly 35 from the inner portion of the same from the upper edge of the inner end of the slit in the tube and terminating at the beginning of the slit in the shuttle-body, substantially as described.

40 2. The combination with a shuttle-body having a delivery-eye extending through one side thereof and a threading-slit communicating with the said eye, of the educt-tube extending transversely of the shuttle with its 45 outer portion located in the said delivery-eye, the said tube having the threading-slit which is reached through the said slit in the shuttle-body and also having the threading-tongue

projecting from the inner portion of the same above the inner end of the slit in the tube, 50 and the inwardly-projecting lips or spurs at the outer end of the said slit to prevent escape of the yarn from the interior of the tube, substantially as described.

3. The combination with a shuttle-body 55 having a delivery-eye extending through one side thereof, a threading-slit communicating with the said eye, and a depression, as 6, of the educt-tube extending transversely of the shuttle with its outer portion cylindrical and 60 located in the said delivery-eye, the said tube having the threading-slit which is reached through the said slit in the shuttle-body, and also having the threading-tongue extending from the upper edge of the inner portion of 65 the same above the inner end of the slit in the tube and projecting into the said depression with its tip adjacent the bottom of the latter and terminating at the beginning of the slit in the shuttle-body, substantially as 70 described.

4. The educt-tube formed with the threading-slit, the tongue extending from the inner portion of the same above the inner end of the said slit, and one or more inwardly-projecting lips or spurs at the outer end of the 75 said slit, substantially as described.

5. The combination with a shuttle-body having a delivery-eye extending through the side thereof, a threading-chamber, a vertical 80 slit extending downward as well as diagonally backward and outward from the said chamber to the exterior of the shuttle-body, and a horizontal slit intersecting both the said vertical slit and the delivery-eye, of the 85 educt-tube with its outer end located in the said delivery-eye and having the threading-slit and the threading-tongue extending from its upper side above the inner end of the said 90 threading-slit, substantially as described.

In testimony whereof I affix my signature in presence of two witnesses.

STEPHEN M. HAMBLIN.
